United States Patent Office

Des. 234,064

Patented Jan. 14, 1975

234,064

CHAIR

Akihiko Node and Akira Hirose, Tokyo, Japan, assignors to France Bed Co., Ltd., Tokyo, Japan

Filed Feb. 28, 1973, Ser. No. 336,485

Term of patent 7 years

Int. Cl. D6—01

U.S. Cl. D6—70

FIG. 1 is a top plan view of a chair showing our design;
FIG. 2 is a front elevational view thereof;
FIG. 3 is a bottom plan view thereof;
FIG. 4 is a right side elevational view thereof;
FIG. 5 is a rear elevational view thereof; and
FIG. 6 is a perspective view thereof.
The left side elevational view is a mirror image of
FIG. 4 and is omitted.

We claim:

The ornamental design for a chair, as shown and described.
